No. 890,404.

PATENTED JUNE 9, 1908.

H. E. BROCKMAN,
SAFETY GAS COCK.
APPLICATION FILED MAR. 13, 1908.

UNITED STATES PATENT OFFICE.

HARRY E. BROCKMAN, OF SIOUX CITY, IOWA, ASSIGNOR OF ONE-HALF TO J. H. JONES, OF SIOUX CITY, IOWA.

SAFETY GAS-COCK.

No. 890,404.

Specification of Letters Patent.

Patented June 9, 1908.

Application filed March 13, 1908. Serial No. 420,829.

To all whom it may concern:

Be it known that I, HARRY E. BROCKMAN, citizen of the United States, residing at Sioux City, in the county of Woodbury and State of Iowa, have invented certain new and useful Improvements in Safety Gas-Cocks, of which the following is a specification.

It is well known that asphyxiation has frequently been caused by the accidental extinguishing of a gas burner, owing to a diminution in the gas pressure or the blowing out of the gas flame or the like, no means being provided for the subsequent and prompt cutting off of the gas supply from the burner and my invention has for its object a simple, durable and efficient construction of device that will effectively prevent such accidents by at once automatically shutting off the gas as soon as the flame has been extinguished.

20 And a further object of the invention is a device of this character which may be cheaply installed and easily applied to any ordinary gas burner without the necessity of material changes in the gas bracket and without in 25 any wise affecting the efficiency of the burner.

With these and other objects in view as will more fully appear as the description proceeds, the invention consists in certain constructions, arrangements and combinations 30 of the parts that I shall hereinafter fully describe and then point out the novel features in the appended claims.

For a full understanding of the invention, reference is to be had to the following description and accompanying drawings, in which:

Figure 1 is a perspective view of a safety gas burner embodying the principles of my invention; Figs. 2 and 3 are front views of the burner, the parts being illustrated in Fig. 10 2 in a position to cut off the gas supply in Fig. 3 to permit the gas to flow; and, Fig. 4 is a perspective view illustrating a slightly modified arrangement of parts for securing one element of the device to the gas bracket.

45 Corresponding and like parts are referred to in the following description and indicated in all the views of the drawings by the same reference characters.

Referring to the drawing, the numeral 1 50 designates a gas bracket or supply pipe of any desired character or design which may or may not be provided with the ordinary manually operated turning plug 2.

3 designates the burner secured to the 55 outer end of the supply pipe or bracket 1 and

mounted upon the casing of a cut-off cock which is preferably of the turning plug variety, the plug or axis thereof being indicated at 4. This cut-off cock, may, if desired, be of that ordinary type which is often employed at the burner for diminishing or increasing the light, the axis carrying at one end a disk formed with lugs 5 and 6 adapted to alternately abut against a lug 7 projecting out from the casing of the cock so as to limit the movement of the plug in one direction or the other.

The axis or plug 4 of the cut-off cock is provided at its opposite end with a head 8 formed with a transverse bore extending therethrough in which a rod-like lever 9 is 70 mounted. One arm of this lever is returned upon itself as indicated at 10 and is thence extended upwardly as indicated at 11 to form a detent so disposed as to oscillate in a vertical plane at right angles to the axis of the cut-off cock when the latter is turned. A compression spring 12 is secured at one end to the opposite arm of the rod-like lever 9, as clearly illustrated in the drawings, the other 80 end of said spring being secured to an apertured projection or hook 13 soldered or otherwise attached to the burner at the base thereof or to some other stationary portion of the fixture.

85 14 designates a pull rod or chain which is secured to the first-named arm of the lever 9 preferably at the bend thereof and which is designed to rock the plug of the cut-off cock against the tension of the spring 12 so as to 90 turn the cock to open position.

In order to hold the cock 4 in open position, so long as the flame issuing from the tip of the burner 3 is inextinguished, I provide the thermostatic rod 15 which is held in a 95 preferably erect position upon the gas supply pipe or bracket 1; being formed with an offset looped end 16 secured directly to the supply pipe 1, as by means of a screw 17 screwing in a socket drilled in the supply pipe. The rod 15 projects upwardly parallel to the burner 3 and it is provided at its upper end with a cross bar or arch 18 and thence extends downwardly in close proximity to the burner tip, as best seen in Fig. 1, the free extremity of the rod being laterally disposed as indicated at 20 and projecting in a plane at right angles to the plane of movement of the detent 11 and normally just out of the path of movement of the extremity of said detent. 110

If desired, the rod 15 may be secured to the supply pipe 1 as illustrated in Fig. 4, by a clip or band 17 encircling the lower offset end 16 of the rod and the supply pipe and 5 clamped to the latter by a screw or the like.

In the practical use of my improved safety gas burner, the pull cord or chain 14 is pulled downwardly by hand and the gas is lighted and the cut-off cock is held open manually 10 for a moment until the heat of the flame expands the thermostatic rod 15, or rather the depending portion 19 thereof, sufficient to cause the laterally disposed extremity 20 to engage with the extremity of the detent 11 15 and thus maintain the cock open so long as the gas is burning. Should, however, the gas be extinguished from any cause, it is manifest that the thermostatic rod will at once cool off and contract so as to carry the 20 keeper constituted by the portion 20 out of engagement with the extremity of the detent 11, thereby permitting the spring 12 to act and at once automatically move the cut-off cock to the closed position and shut off 25 the supply of gas.

Having thus described the invention, what is claimed as new is:

1. In a device of the character described, the combination with a supply pipe and 30 burner, of a turning plug controlling the supply of gas from the pipe to the burner, a lever secured to the plug and having arms projecting in opposite directions therefrom, a contractile spring secured to one of said arms and 35 exerting a tension thereon to automatically turn the plug to closed position, the other arm of said lever being returned upon itself with its extremity projecting upwardly and disposed so as to oscillate in a vertical plane

40 at right angles to the axis of the plug, a thermostatic rod and means for supporting the same in proximity to the burner, said rod being provided with a lateral extremity arranged close to the extremity of the detent, 45 a pull-cord secured to the said other arm of the lever, as and for the purpose set forth.

2. In a device of the character described, the combination with a supply pipe and burner, of a turning plug arranged to control the supply of gas from the pipe to the burner, 50 a detent carried by said plug and mounted to oscillate in a plane at right angles to the axis of the plug, and a thermostatic rod formed with an offset lower end and with an opposite extremity arranged close to the 55 burner and to the free extremity of the detent, and means for securing the offset lower end of the rod to the supply pipe.

3. In a device of the character described, the combination with a supply pipe and 60 burner, of a turning plug arranged to control the supply of gas from the pipe to the burner, a detent carried by said plug and mounted to oscillate in a plane at right angles to the axis of the plug, a thermostatic 65 rod formed with an offset lower end and with an opposite extremity arranged close to the burner and to the free extremity of the detent, the lower offset end of the rod being looped, and means securing the offset and 70 looped lower end of the rod to the supply pipe.

In testimony whereof I affix my signature in presence of two witnesses.

HARRY E. BROOKMAN [L. S.]
